BICYCLE LUGGAGE CARRIER

Viktor Schreckengost, Cleveland Heights, Ohio, assignor
to The Murray Ohio Manufacturing Co., Nashville,
Tenn., a corporation of Ohio

Continuation of design applications, Ser. Nos. 74,033 and
74,034, Mar. 19, 1963. This application June 16,
1964, Ser. No. 80,539

Term of patent 14 years

(Cl. D90—3)

Fig. 2.

Fig. 4.

Fig. 3.

Fig. 5.

Fig. 6.

Fig. 7.

Fig. 8.

FIGURE 1 is a side elevational view of a first embodiment of a bicycle luggage carrier showing my new design;

FIGURE 2 is a top plan view thereof;

FIGURE 3 is a rear elevational view thereof;

FIGURE 4 is a perspective view thereof;

FIGURE 5 is a side elevational view of a second embodiment of a bicycle luggage carrier showing my new design;

FIGURE 6 is a top plan view thereof;

FIGURE 7 is a rear elevational view thereof; and

FIGURE 8 is a perspective view thereof.

The fragmentary portions of a bicycle shown in broken lines in FIGURES 1 and 5 are included for illustration purposes only.

This application is a continuation of the following applications: Serial No. D-74,034, filed March 19, 1963; Serial No. D-74,033, filed March 19, 1963, and now abandoned.

I claim:

The ornamental design for a bicycle luggage carrier, substantially as shown and described.
